PROTECTIVE COVER FOR BOOKS

Eli Davidson, Dorchester, Mass.

Application January 25, 1939, Serial No. 252,708

5 Claims. (Cl. 281—34)

This invention relates to a protective cover to be used for temporarily encasing a book while it is being read or used, in order to protect the book from becoming soiled or marred.

- 5 One of the objects of the invention is to provide a protective cover which can be easily applied to or removed from the book and which is constructed so that it will readily fit books of different sizes.
- 10 A further object of the invention is to provide a protective cover in which the portions that enclose the covers of the book have sufficient stiffness so that when the device is applied to a paper covered book, it will provide a book having relatively stiff covers.

Further objects of the invention are to provide a protective cover for books having various novel features which will be more fully herein-after set forth.

- 20 In the drawings wherein I have illustrated some embodiments of the invention,

Fig. 1 is a perspective view of the cover member for one cover of the book and its associated sheet for wrapping around the book;

- 25 Fig. 2 is a perspective view of the cover member for the other cover of the book;

Fig. 3 is a sectional view illustrating my improved protective cover applied to the book, the book being shown in dotted lines;

- 30 Fig. 4 is a section on the line 4—4, Fig. 3;

Fig. 5 is a view illustrating a cover member for one of the book covers having a different construction from that shown in Fig. 1;

- 35 Fig. 6 is a perspective view of the cover sheet to be used with the cover member shown in Fig. 5;

Fig. 7 is a perspective view for the cover member of the other cover of the book to be used with the cover sheet shown in Fig. 6;

- 40 Fig. 8 is a sectional view showing one cover member and the cover sheet applied to the book and the other cover member about to be applied to one of the book covers, the book being shown in dotted lines;

- 45 Fig. 9 shows the construction of one of the extensible sections of the cover member illustrated in Fig. 1;

- 50 Fig. 10 shows the construction of the other extensible section of the cover member illustrated in Fig. 1.

In Figs. 5 to 8 I have shown a simple embodiment of the invention which will first be described.

- 55 The protective cover shown in said figures comprises a cover member 1 having a pocket 2 to

receive the outer edge portion of the cover 3 of the book 4, a cover sheet 5 of flexible material adapted to wrap around the book cover and a second cover member 7 similar to the cover member 1 and having a pocket 6 adapted to receive the outer edge portion of the other cover 8 of the book 4.

The cover members 1 and 7 may be made of any suitable material but will preferably be made of paper having some stiffness and body so that the 10

cover members 1 and 7 will be relatively stiff. Each cover member is formed with the two sides 9 and 10 which are secured together along the top and bottom edges 11 and 12 of said member and also along the front edge 13, said sides 9 and 10 being unattached along the edge opposite the edge 13a, thereby to provide a pocket 2 which is open along said opposite edge. In the construction shown each of the cover members 1 and 7 is made from a blank which is folded to present 15 the two tabs 14 and 15 at the top and bottom edges, and then is folded along the line 13 to bring the side 10 into overlapping relation to the tabs 14 and 15, said side being adhesively secured to the tabs, thereby making the cover member with the pocket open at one edge.

The cover sheet 5 may be formed of any suitable flexible material, either paper or fabric. In using the protective cover, the cover sheet 5 is first wrapped around the back 16 of the book 4 30

and is placed in position overlying the outer faces of the book covers 3 and 8. The edge portion 17 of the cover member is then folded around the outer edge 18 of the book cover 3,

while the opposite edge portion 19 of the cover sheet 5 is folded around the outer edge 20 of the other book cover 8, as shown in Fig. 8. The two cover members 1 and 7 are then slipped on 35

to the book covers, the outer edge of each book cover with the edge portion of the cover sheet 30

folded thereabout being entered into the pocket 2 or 6 of the cover member.

These cover members 1 and 7 may be made of a size to receive the entire book cover 3 or 8, or

may be of a smaller size sufficient to receive 45 only the outer edge portions of the book covers, as shown in the drawings. In either case, how-

ever, the edge portions 17 and 19 of the cover sheet 5 which are folded around the outer edges 18 and 20 of the book covers will be held in this 50 folded position by the cover members 1 and 7 and the protective cover will thus be securely retained on the book while it is being used.

The device illustrated in Figs. 5 to 8 can be used equally well with a book of a given dimen- 55

sion from the top to the bottom regardless of either its thickness or its width, that is, the dimension from the outer edge 18 or 20 of the book cover to the back of the book. The cover sheet 5 will be of sufficient length to enclose the covers of a wide thick book and if the device is used on a narrower or thinner book, the only result will be that a greater portion of the edges 17 and 19 of the cover sheet will be folded around the edges 18 and 20 of the book covers. Cover members 1 and 7 which are of a dimension to fit a narrow book can be used equally well on a wide book. In the case of a wide book, that is a book having a large dimension 15 from the edges 18 and 20 of the book covers to the back of the book, the cover members 1 and 7 will cover a smaller portion of the book cover than in the case of a narrow book, but in either case, these cover members will hold the cover sheet securely in position around the book.

The protective cover can be easily applied to a book in the manner above described, and it can be just as easily removed from the book by simply withdrawing the cover members 1 and 7 from the book covers and then removing the cover sheet 5.

In order to assist in removing the cover members 1 and 7 from the book covers, I have illustrated each cover member as provided with a tape or ribbon 21, one end of which tape or ribbon is secured to the outer side 9 of the cover member by adhesive or some other suitable means. When the cover member is applied to the book cover, said tape or ribbon 21 will extend from the outer edge of the outer face 9 of said cover member around the edge of the book cover, as shown at 22, and then will extend along between the book cover and the inner side 10 of the cover member, the end 23 of said ribbon or tape being exposed on the inside of the book cover. By grasping this exposed end 23 of the ribbon and applying a pulling force thereto, the cover member 1 will be forced off from the book cover.

Instead of making both cover members separate from the cover sheet, I may permanently attach the cover sheet to one cover member and have the other cover member free to be applied to the book cover, as shown in Figs. 5 to 8. Such an embodiment is shown in Figs. 1 to 4.

Figs. 1 to 4 also show a construction in which the cover members are made extensible in a direction from the top to the bottom of the book, so that the cover member can be used equally well with short books or tall books. In the construction shown in Figs. 1 to 4 also, the cover sheet is made extensible in a direction from the top to the bottom of the book.

In Figs. 1 and 2, the two cover members are indicated generally at 24 and 25, and the cover sheet is shown at 26. Each cover member is made in two sections having a telescopic relation and capable of being extended in a direction from the top to the bottom edge. The two sections of the cover member 24 are indicated at 27 and 28, and the two telescopic sections of the cover member 25 are indicated at 70 and 71.

The section 27 of the cover member 24 is formed with the inner wall 29 and the outer wall 70 30, said walls being connected together at the bottom 31 of the cover member but disconnected at the top. The inner section 28 of the cover member comprises the two side walls 32 and 33 which are connected together at the top, as shown at 34, but are disconnected at the bot-

tom. The inner member 28 fits within the outer member 27 and has a telescopic relation therewith so that the inner member 28 may be pulled more or less out of the outer member, as shown by dotted lines, Fig. 1, thereby extending the 5 cover members in the direction from the top to the bottom of the book.

The sides 29 and 30 of the outer section 27 as well as the sides 32 and 33 of the inner section 28 are disconnected along the edge 35 of the 10 cover member, thereby providing the open pocket into which the outer edge of the book cover can be inserted. In the embodiment shown in Fig. 1 the cover sheet 26 comprises the two sections 36 and 37 which have an overlapping relation. The 15 section 36 of the cover sheet 26 is secured at its lower edge to the outer wall of the outer section 27 and the cover sheet section 37 is secured at its upper edge to the outer wall 33 of the inner section 28 of the cover member. As a result, 20 when the two sections 27 and 28 are extended to be applied to a tall book, the cover sheet sections 36 and 37 will be similarly extended and will thus enclose the back of such tall book. The cover sections 36 and 37 may be secured to the 25 cover member sections 27 and 28 in various ways. As herein shown, the cover section 28 is formed from a blank such as shown in Fig. 9 which is folded centrally along the line 50 to form the inner and outer walls 32 and 33. The blank is 30 formed with a tab 51 at the upper end of the inner wall 32, which tab is folded inwardly as seen in Fig. 1, the exposed face of the tab being coated with adhesive 52. One end of the cover sheet section 37 overlies the inner face of the 35 outer wall 33 of the cover section 28 and is secured to said wall near its upper edge by staples 53, adhesive, or any other suitable fastening means. After the cover sheet section has thus been secured to the wall 33, the two walls 32, 33 40 are folded together and the tab 51 is adhesively united to the wall 33 and the overlapping portion of the sheet section 37. The cover section 28 is then ready for assembling with the other cover section 27.

The cover section 27 may be made from a blank having the shape shown in Fig. 10. This blank comprises the two sections 29 and 30 which are folded together along the line of fold 54, and which form the inner and outer walls of the cover section 27. The inner wall 29 has an infolded tab 55 at one edge and the outer wall 30 has a similar infolded tab 56 at its free edge. The wall 29 also has an upturned tab 39 at its lower edge which overlies the outer face of the cover sheet section 36 at its lower edge and is secured thereto in some suitable way as by means of staples 58. The outer face of the tab 39 is shown as having a coating of adhesive 59 by which said tab is secured to the inner face of the outer wall 30, as shown in Fig. 60 4, when the two walls are folded together to complete the cover section 27. The lower corner 60 of the tab 56 may be folded around the end of the tab 39 and tucked between said tab and the cover sheet section 36.

The two cover sections 27 and 28 with their attached cover sheet sections 36 and 37 are assembled by sliding the free edge 61 of the wall 32 of the cover section 28 between the wall 29 of the cover section 27 and its infolded tab 55 70 and at the same time sliding the free edge 62 of said cover section 28 between the wall 30 of said cover section 27 and its tab 56, said tabs 55 and 56 constituting guides for said edges 61 and 62. In thus assembling the cover sections the sheet 75

section 37 may be placed either on the outside or on the inside of the sheet section 36. If it is located on the outside, as shown in Figs. 1, 3 and 4, then the lower edge 63 thereof will be entered between the upper edge 64 of the cover sheet section 36 and the infolded tab 56. If the sheet section 37 is to be located on the inside of sheet section 36, then in assembling the cover sections, the upper edge 64 of the sheet section 36 will be entered between the lower edge of the sheet section 37 and the wall 33.

The two sections 70 and 71 of the extensible cover member 25 may have the same construction as the sections 27 and 28 of cover member 24, except that there are no cover sheet sections attached to the cover sections.

In this embodiment of the invention, each cover member may be provided with the tab or ribbon 42 similar to the ribbon 21, and by which the cover members can be readily removed from the book cover.

Where the cover members are made in extensible sections, as shown in Figs. 1 to 4, I prefer to provide means for connecting the sections so as to prevent them from being entirely separated, and such means may conveniently be in the form of an elastic band or ribbon which will yieldingly hold the cover member sections in their contracted position shown in full lines, Fig. 1, but which will allow them to be extended. The advantage of this construction is that when the cover members are thus extended to be applied to a long book, the elasticity of the elastic members will tend to contract the cover member sections and thus automatically reduce them to a size to fit the particular book to which they are applied. Such elastic connecting means is shown as an elastic ribbon 44 which is placed between the outer wall 29 of the outer cover member section 27 and the outer wall 32 of the inner cover member section 28. This elastic band or ribbon is shown as adhesively or otherwise secured to the wall 29 of the outer cover member section 27, as shown at 45, and is adhesively or otherwise secured to the outer wall 32 of the inner cover member section 28, as shown at 46. Thus, when the cover member sections are extended, the band or ribbon 44 will be stretched, and when the extended cover members are applied to a book, the elasticity of said band or ribbon will tend to reduce the vertical dimensions of the sectional cover members to correspond to that of the book covers to which they are applied.

In applying this device to a book, one cover 3 of the book 4 will be inserted into the pocket of the extensible cover member 24, that is, the cover member to which the cover sheet 26 is secured, and then said sheet 26 will be wrapped around the back 18 of the book and the edge 47 thereof folded around the edge 48 of the book cover 8, as shown in Fig. 3. The other cover member 25 is then applied to the book cover 8 thereby holding the edge 47 of the cover sheet folded around the edge of the book cover 8.

In Figs. 1 and 3 I have shown the cover sheet as provided with a book mark which can be used when the cover is applied to the book. This book mark is in the form of a ribbon 80 which is attached to the cover sheet near its upper edge so that when the cover is applied to a book, the book mark will be located at the back of the book in position to be placed between the leaves of the book in any desired location.

In order to provide a book mark which is adaptable for books of different thicknesses, I propose

to adjustably secure the book mark to the cover sheet. As herein shown, the cover sheet has a strap 81 secured to its inner face near its top edge, said strap being secured to the cover sheet at its ends 82. The book mark ribbon 80 is formed with a loop 83 through which the strap 81 extends, and since the strap is secured to the cover sheet at its ends only, the loop 83 of the book mark can be slid back and forth on the strap so as to bring the book mark into proper position to be used with books of different thicknesses.

Where the cover sheet is a two-section sheet as shown in Fig. 1, I propose to attach the book mark to the upper portion of the outer cover sheet section 37.

The cover sheets 5 or 26 may be made from any suitable material such as paper, fabric, Cellophane, etc. If Cellophane or some other transparent material is used, then the title of the book as printed on the back thereof can be readily read through the cover sheet.

I claim:

1. The combination with a book, of a protective cover therefor comprising two cover members, each having a pocket to receive at least the outer edge portion of the cover of a book, and a cover sheet of flexible material extending from one cover member around the back of the book to the other cover member, the free edge of the cover sheet being folded around the edge of the corresponding book cover and being clamped thereto by the corresponding cover member, one of the cover members having a tape within its pocket which extends around the edge of the book cover, one end of said tape being secured to the cover member adjacent the mouth of the pocket and the other end being exposed beyond the cover member whereby the application of a pulling strain to the exposed end of the tape will force the cover member off from the book cover.

2. The combination with a book having book covers, of a protective cover for said book comprising a cover member having a pocket to receive at least the outer edge portion of one of the book covers, a cover sheet of flexible material permanently secured to said cover member, said cover sheet extending around the back of the book and having its free end folded over the outer edge of the other book cover and lying against the inner face of said book cover, and a second cover member separate from and unconnected with the first cover member and having a pocket in which is received the edge portion of the other book cover about which the free end of the cover sheet is folded, said second cover member being removably applied to the book cover and serving to hold the cover sheet folded about the edge thereof.

3. The combination with a book having book covers, of a protective cover for said book comprising a cover member having a pocket to receive at least the outer edge portion of one of the book covers, a cover sheet of flexible material permanently secured to said cover member, said cover sheet extending around the back of the book and having its free end folded over the outer edge of the other book cover and lying against the inner face of said book cover, a second cover member separate from and unconnected with the first cover member and having a pocket in which is received the edge portion of the other book cover about which the free end of the cover sheet is folded, said second cover member being removably applied to the book cover and serving to hold

the cover sheet folded about the edge thereof, each cover member and the cover sheet being made in sections which can be adjusted relative to each other to accommodate books having different dimensions from the top to the bottom, and elastic means connecting the sections of each book cover.

4. The combination with a book having book covers, of a protective cover for said book comprising a cover member having a pocket to receive at least the outer edge portion of one of the book covers, which cover member is made in two sections having a telescopic relation, elastic means yieldingly connecting said sections, a cover sheet 10 of flexible material made in two sections, one connected to each section of the cover member, said cover sheet extending around the back of the book and having its free end folded over the outer edge of the other book cover, and a second cover member 15 also formed in two sections having a telescopic relation together with elastic means connecting said sections, said second cover member being separate from and unattached to the cover

sheet and being removably applied to the other book cover and serving to hold the cover sheet folded about the edge of said other book cover.

5. The combination with a book having book covers, of a protective cover for said book comprising a cover member having a pocket to receive at least the outer edge portion of one of the book covers, a cover sheet of flexible material permanently secured to said cover member, said cover sheet extending around the back of the book and having its free end folded over the outer edge of the other book cover and lying against the inner face of said book cover, a second cover member 10 separate from and unconnected with the first cover member and having a pocket in which is received the edge portion of the other book cover about which the free end of the cover sheet is folded, said second cover member being removably applied to the book cover and serving to hold the cover sheet folded about the edge thereof, and a book mark adjustably but permanently secured to the cover sheet adjacent its upper edge. 15 20

ELI DAVIDSON.
